UNITED STATES PATENT OFFICE.

HENRY M. KOFSKY, OF PHILADELPHIA, PENNSYLVANIA.

BRACKET.

Application filed June 20, 1924, Serial No. 721,813. Renewed August 13, 1925.

To all whom it may concern:

Be it known that I, HENRY M. KOFSKY, a citizen of the United States, residing at Philadelphia, in the county of Philadelphia and State of Pennsylvania, have invented 5 certain new and useful Improvements in Brackets, of which the following is a specification.

The object of this invention is to provide 10 an improved bracket, particularly designed and adapted for use in securely attaching lighting fixtures to a wall.

I aim to adapt the bracket for attachment 15 by the usual screws to a standard outlet box through which the ends of electric conductors are made available for connection to the wires and lamps of a fixture.

I also aim to adapt such a bracket for 20 supporting wall fixtures by a plurality of different means, according to their own provisions for support: i. e., some fixtures have a recessed plate with a bar to be directly supported by the bracket; while other fixtures 25 have a plate (either recessed or solid) without a bar, but generally provided with an aperture for a securing member to hold the fixture to the bracket. In this latter case, a threaded nipple or bolt as securing member generally has one end engaged in 30 a threaded aperture in the bracket, and an ornamental nut threaded on its other end. In either case, the assembled parts securely 35 yet removably attach the fixture to the outlet box, and thus to the wall.

With the foregoing and other objects in view, the present invention comprises additional novel details of construction and operation hereinafter fully brought out in 40 the following description, when read in conjunction with the accompanying drawings, in which Fig. 1 is a vertical transverse sectional view of an outlet box and an electric light fixture secured thereto by means of a nipple; Fig. 2 is a similar section showing 45 the fixture secured by means of a bar entirely hidden from the front of the plate; Fig. 3 is a horizontal sectional view of the plate of Fig. 2 per se; and Fig. 4 is a perspective view of the improved bracket per se.

Referring to the drawings, an electric lighting fixture is illustrated as comprising 50 a concave back-plate 1 having an ornamental marginal corrugation 2 terminating in a peripheral flange 3, which in practice abuts directly against the wall 4 to which the fixture is secured. Substantially centrally

of said plate is an aperture 5 through which projects outwardly a threaded nipple 5^a, carrying upon its outer free end an ornamental or other desired form of nut 6. A 60 second aperture 7 in said plate permits electric conductors (not shown) to extend from the rear of the plate toward and through the fixture arm 8, also secured to said plate, and carrying upon its outer end (for example) a suitable socket 9, a "candle" extension 10, and an electric light bulb 11.

As usual, the wall 4 has a recess with a standard outlet box therein. This outlet box 70 comprises a top wall 12 and a bottom wall 13, connected by a rear wall 14 and opposite side walls 15 (the nearer of which latter is not shown). The upper and lower walls are provided with suitable means 16 for securing the box to any convenient adjacent portion of the wall recess, and also with upwardly and downwardly extending projections 17 and 18, each having a threaded aperture to receive a screw 19.

Referring to Fig. 4, the preferred embodiment of the invention here shown comprises a body portion 20 provided at one end with a laterally elongated aperture 21, and at its other end (preferably) reduced extension 80 as at 22 to afford more room beside it for electric conductors and provided with a laterally elongated aperture 23—the purpose of 85 said apertures being, as shown in Figs. 1 and 2, to receive the outer portions of the screws 19 above referred to.

The body portion of the bracket is provided, substantially midway between the apertures 21 and 23, with a threaded aperture 24, surrounded by a substantially cylindrical flange formed by first creating a smaller hole 90 than desired and then drawing the metal surrounding said hole outwardly. Such flanging of the aperture 24 affords a longer threaded surface and thus assures greater 95 contact and more rigid relations between the bracket and box and the nipple 5.

The bracket is also provided with an L-shaped, upwardly extending hook 25, spaced and, as shown in Fig. 4, punched from the body portion between the apertures 21 and 24. This hook portion 25 is so located as to be in line with and receive therethrough, in a transverse direction, a bar 26 which extends between and is attached to laterally opposite regions of the inner (normally hidden) surfaces of the corrugations 2 and flange 3.

When a fixture of the type shown from and secured to Fig. 1 is being installed, it is supported in the outlet box by means of the nipple 5 secured in the aperture 24 of the improved bracket—the nut 6, and without regard to the hooked portion 25 of the bracket. On the other hand, when the fixture embodies a plate having no provision for the use of the nipple 5^a, but instead provided with the bar 26, said bar is caught over the hooked portion 25 of the bracket and the fixture secured in position as shown in Fig. 2. Thus, there is provided what might well be termed a universal bracket, of efficient operations, and obviously characterized by low cost of production.

Having thus described my invention, what I claim and desire to protect by Letters Patent of the United States is:—

20 1. A bracket of the character described having a body portion with apertures adjacent its ends, a hook spaced from the body portion of said bracket between said apertures, and also a threaded aperture between said first-named apertures; said hook being adapted either with or independently of said last named aperture to receive and support a part of a fixture.

25 2. A bracket having a body portion provided adjacent to its ends with apertures, a threaded aperture positioned between said first-named apertures, and a hooked portion struck out from the body portion of said bracket and adapted either with or independently of said last-named aperture to receive and support a part of a fixture.

30 3. A bracket of the character described having a body portion with apertures adjacent its ends, a threaded aperture between said first-named apertures, and a hook spaced from the body portion of said bracket between one of said first-named apertures

and said last-named aperture, and adapted either with or independently of said last-named aperture to receive and support a part of a fixture.

4. A bracket for securing a wall fixture to an outlet box having a body portion reduced to afford room beside it for electric conductors and provided with apertures adjacent its ends adapted to receive supporting screws carried by the outlet box, and also having an intermediate aperture internally screw-threaded to receive a corresponding threaded nipple or bolt for attaching a fixture to the bracket.

5. A bracket having a body portion provided adjacent to its ends with laterally elongated apertures adapted to receive supporting screws carried by an outlet box, a third aperture positioned between said first apertures, the metal surrounding said third aperture being drawn axially to form a cylindrical cross-section and internally threaded to receive a correspondingly threaded nipple or bolt for attaching a fixture to said bracket.

6. A bracket having a body portion provided adjacent to its ends with laterally elongated apertures adapted to receive supporting screws carried by an outlet box, a third aperture positioned between said first apertures, the metal surrounding said third aperture being drawn axially to form a cylindrical cross-section and internally threaded to receive a correspondingly threaded nipple or bolt for attaching a fixture to said bracket, and a hook spaced from said body portion and adapted to support thereon the weight of a fixture, either with or independently of said threaded aperture.

In testimony whereof I have affixed my signature.

HENRY M. KOFSKY.
